[57] CLAIM

The ornamental design for a collapsible shade, as shown
and described.

DESCRIPTION

FIG. 1 is a front elevational view of the collapsible
shade showing a use of my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of a lamp in FIG. 1 is for
illustrative purposes only and forms no part of the
claimed design.

*FIG. 1**FIG. 2**FIG. 3*

FIG. 4

FIG. 5

FIG. 6
